UNITED STATES PATENT OFFICE.

ARTHUR TREVOR DAWSON AND GEORGE THOMAS BUCKHAM, OF WESTMINSTER,
LONDON, ENGLAND, ASSIGNEES TO VICKERS LIMITED, OF WESTMINSTER,
ENGLAND.

AUTOMATIC GUN.

1,262,181.

Specification of Letters Patent. Patented Apr. 9, 1918.

Application filed April 7, 1915. Serial No. 19,845.

To all whom it may concern:

Be it known that we, Sir ARTHUR TREVOR DAWSON, Knight, and GEORGE THOMAS BUCKHAM, both subjects of the King of Great Britain, residing at Vickers House, Broadway, Westminster, in the county of London, England, have invented certain new and useful Improvements in or Relating to Automatic Guns, of which the following is a specification.

This invention relates to automatic guns of the well known kind in which the barrel recoils and the breech mechanism comprises a reciprocating lock provided with a vertically movable cartridge carrier and adapted to recoil in suitable guides against the resistance of a spring, the lock being connected to an extension on the barrel by toggle levers of which the rear one (termed the crank) is pivoted to the said extension, and the other (termed the connecting rod) is connected at one end to the crank and at the other end to the lock. These toggle levers serve to impart to the lock the necessary reciprocating movements relatively to the barrel for causing the cartridge carrier during the rearward movement of the lock to extract the used cartridge case from the barrel and a new one from the cartridge bolt and during the forward movement of the lock to insert the new cartridge into the barrel and eject the used cartridge case, the movements of the said carrier being effected by lifting levers and by side cams with which lateral horns on the said carrier engage. The chief object of the present invention is to so construct and arrange the breech mechanism that a comparatively long recoil of the barrel can be obtained for the purpose of diminishing the shock on the gun trunnions when the gun is fired.

According to the present invention the mechanism is so constructed and arranged that during the recoil of the barrel the crank is angularly displaced about its axis to initially bend the toggle levers and during the return of the barrel the said crank continues its movement in the same direction and completes the bending of the toggle levers whereby the lock is restrained from following the barrel until the latter approaches or reaches its forward position. For this purpose the crank may be provided with a projection which co-operates with a stop on the mechanism casing to prevent the lock from fol-

lowing the barrel on its forward movement until the barrel approaches or reaches its forward position, whereupon the movement of the crank shaft with the barrel causes the projection on the crank to become liberated from the stop and the lock to be moved to its forward position by a spring.

The aforesaid cams for controlling the cartridge carrier instead of being stationary as heretofore, are carried by the barrel extension so that the carrier is held in its raised position during the recoil of the barrel together with the lock but is permitted to drop during the forward movement of the barrel without the lock.

In order to avoid the liability of the carrier remaining in its raised position when its horns are clear of the upper surface of the cams (which might happen when the gun is firing at large angles of elevation or depression) we may employ a spring or cam controlled lever or arm, pivoted to the mechanism casing, for co-operating with the carrier or with its horns, so that when these horns are clear of the upper surface of the cams the carrier is moved downward to bring the new cartridge therein opposite the barrel chamber.

In order that the said invention may be clearly understood and readily carried into effect, we will describe the same more fully with reference to the accompanying drawings, in which:—

Figures 1, 2 and 3 are respectively a side elevation, a vertical longitudinal section and a plan (with the cover removed) showing an automatic gun constructed in accordance with our invention.

Fig. 4 is a vertical longitudinal elevation showing the position of the parts when the barrel is at full recoil.

Fig. 5 is a view similar to Fig. 4, with the barrel in its forward position and the lock on the point of being released to enable it to move forward, and

Figs. 6, 7 and 8 are diagrammatic views showing the position of the aforesaid lever or arm in relation to the side cams and the cartridge carrier, the parts being shown with the barrel in the fully recoiled position, the barrel returning after recoil and the barrel approaching its forward position.

A is the recoiling barrel, B the reciprocating lock carried in guides in the mechanism casing B', and B² the cartridge carrier mov-

ably mounted in the lock B. C, C' represent the toggle levers of which the lever C, termed the crank, is pivotally connected by the crank shaft C² to an extension A' on the 5 barrel, and C' is termed the connecting rod and is connected at one end to the crank and at the other end to the lock. D, D are the side cams which coöperate with horns on the cartridge carrier B². c represents the 10 aforesaid projection on the crank C and b represents its coöperating stops on the mechanism casing B'.

In the example shown, the crank has two downward extensions, c', c' carrying rollers 5 c'', c'' which, during the initial recoiling movement of the barrel, coöperate with fixed inclines b', b' arranged on the side plates of the mechanism casing. These inclines terminate at their rear in straight guides 10 b'', b'' for the rollers. The aforesaid stop b for coöperating with the projection c on the crank may be in the form of a spring controlled plunger; two such plungers and projections are preferably employed as 15 shown. After the toggle joint has been initially bent by the coöperation of the inclines b', b' with the rollers c'', c'' the continued rearward movement of the crank shaft C² carries the projections c, c into 20 contact with beveled faces on the spring plungers b, b which are displaced against the resistance of their springs to enable the 25 said projections to pass behind them (Fig. 4.) On the forward movement of the barrel taking place under the influence of its 30 return spring A'', the front faces of the projections c, c coöperate with the rear faces of the plungers b, b without lifting the latter, and the barrel moves forward without 35 the lock B, the crank C being further angularly displaced. At the same time the aforesaid side cams D, upon which the horns B² 40 on the carrier have been resting (see Figs. 6 and 7) move clear of these horns and the 45 carrier is then moved downward by levers E pivoted to the mechanism casing and controlled by cam surfaces d on the side cams D. The crank C is also formed with arms c², c² which coöperate with the straight portions b'', b'' of the inclines on the side 50 plates of the mechanism casing to prevent overthrow of the crank. When the projections c, c move clear of the plungers b, b 55 (Fig. 5) the spiral spring inclosed in the casing C causes the crank C to move the lock toward its forward position by the straightening of the toggle levers.

The mechanism casing carries a spring controlled pivoted pawl G which, in the 60 event of the recoil movement of the barrel being insufficient to enable the horns of the carrier B² to become clear of the cams D, D, will lie in the path of the upper portion of the carrier and thus prevent the lock from 65 being moved forward, thereby avoiding the

possibility of a cartridge in the belt being fired by the impact therewith of the nose of the cartridge in the carrier.

The shaft C² of the crank is provided with a handle C² by means of which the 70 breech mechanism can be moved into the open position by hand; in this event, as the side cams D, D for controlling the carrier are attached to the barrel extension which is then stationary, the improved mechanism 75 operates in substantially the same manner as that of the automatic guns at present in use when operated by hand.

What we claim and desire to secure by Letters Patent of the United States is:—

1. In the breech mechanism of automatic guns, the combination with the lock and the toggle levers for operating it, of means for initially bending said toggle levers during the recoil movement of the barrel without 85 completely extracting the cartridge case from the barrel during this movement, and means independent of the first mentioned means for completing the bending of said toggle levers during the forward movement 90 of the barrel to completely extract the cartridge case.

2. In the breech mechanism of automatic guns, the combination with the lock, and the toggle levers for operating the lock, said 95 toggle levers consisting of a crank and a connecting rod interposed between the crank and the lock, of means coöperating with the crank for initially bending the toggle levers during the recoil of the barrel, 100 means independent of the first mentioned means for completing the bending of said toggle levers during the forward movement of the barrel and a spring for imparting a reverse movement to the crank to close the 105 breech as the barrel completes its forward movement.

3. In the breech mechanism of automatic guns, the combination with the lock, the barrel extension, and the toggle levers for 110 operating the lock, said toggle levers consisting of a spring controlled crank pivoted to the barrel extension and a connecting rod interposed between the crank and the lock, of means coöperating with the 115 crank for initially bending the toggle levers during the recoil of the barrel, means independent of the first mentioned means, also coöperating with the crank for completing the bending of said toggle levers during the 120 forward movement of the barrel, the spring of the crank imparting a reverse movement thereto to close the breech when the crank moves clear of the second mentioned means.

4. In the breech mechanism of automatic 125 guns, the combination with the lock, the barrel extension, and toggle levers for operating the lock, said toggle levers consisting of a spring controlled crank pivoted to the barrel extension and a connecting rod inter- 130

posed between the crank and the lock, of a projection on said crank, a member having an inclined surface with which said projection coöperates during the recoil of the barrel to initially bend the toggle levers, means independent of the first mentioned means, coöperating with the crank for completing the bending of said toggle levers during the forward movement of the barrel, the spring of the crank imparting a reverse movement thereto to close the breech when the crank moves clear of the second mentioned means.

5. In the breech mechanism of automatic guns, the combination with the lock, the barrel extension, and toggle levers for operating the lock, said toggle levers consisting of a spring controlled crank pivoted to the barrel extension and a connecting rod interposed between the crank and the lock, of means coöperating with said crank for initially bending the toggle levers during the recoil of the barrel, a projection on said crank, a device coöperating with said projection for completing the bending of the toggle levers during the forward movement of the barrel, the spring of the crank imparting a reverse movement thereto to close the breech when the projection on the crank moves clear of said device.

6. In the breech mechanism of automatic guns, the combination with the lock, the barrel extension, and toggle levers for operating the lock, said toggle levers consisting of a crank pivoted to the barrel extension and a connecting rod interposed between the crank and the lock, of a projection on said crank, a member having an inclined surface with which said projection coöperates, during the recoil of the barrel, to initially bend the toggle levers, a second projection on said crank, and a device coöperating with said second projection for completing the bending of the toggle levers during the forward movement of the barrel.

7. In the breech mechanism of automatic guns, the combination with the lock, the barrel extension, and toggle levers for operating the lock, said toggle levers consisting of a crank pivoted to the barrel extension and a connecting rod interposed between the crank and the lock, of a projection on said crank, a member having an inclined surface with which said projection coöperates, during the recoil of the barrel, to initially bend the toggle levers, a second projection on said crank, and a spring plunger which is displaced by said second projection during the recoil movement of the barrel, and with which said second projection coöperates, during the forward movement

of the barrel, to complete the bending of the toggle levers.

8. In the breech mechanism of automatic guns, the combination with the lock, and the toggle levers for operating it, of means for initially bending said levers during the recoil movement of the barrel without completely extracting the cartridge case from the barrel during this movement, means for completing the bending of said toggle levers during the forward movement of the barrel to completely extract the cartridge case, the cartridge carrier, an extension on the barrel and a side cam carried by said extension for controlling the movements of the said carrier.

9. In the breech mechanism of automatic guns, the combination with the lock and the toggle levers for operating it, of means for initially bending said levers during the recoil movement of the barrel without completely extracting the cartridge case from the barrel during this movement, means for completing the bending of said toggle levers during the forward movement of the barrel to completely extract the cartridge case, the cartridge carrier, a side cam for controlling the movements of said carrier, a member pivoted to a fixed part and adapted to coöperate with said carrier and means for positively causing said member to effect a downward movement of said carrier when the latter is clear of the rear part of the side cam.

10. In the breech mechanism of automatic guns, the combination with the lock and the toggle levers for operating it, of means for initially bending said levers during the recoil movement of the barrel without completely extracting the cartridge case from the barrel during this movement, means for completing the bending of said toggle levers during the forward movement of the barrel to completely extract the cartridge case, the cartridge carrier, an extension on the barrel, a side cam carried by said extension for controlling the movements of the said carrier, a member pivoted to a fixed part and adapted to coöperate with said carrier, said side cam having a cam surface for positively causing said member to effect a downward movement of said carrier when the latter is clear of the rear part of the side cam.

In testimony whereof we affix our signatures in the presence of two witnesses.
